UNITED STATES PATENT OFFICE

2,585,848

SPIRAL PROJECTOR AND PROPELLER

Percy W. Russell, Jacksonville, Ill.

Application December 19, 1946, Serial No. 717,284

3 Claims. (Cl. 46—85)

1

The present invention relates to a game device. More particularly, it relates to a projectile and target type of device wherein different scores are obtained when the projectile lands on different areas of the target.

It is an object of the invention to provide a game device that is interesting to play and which involves a combination of an element of chance and an element of skill.

A particular object of the invention is to provide a projectile in the form of a simulated helicopter, which projectile may be impelled by suitable means and caused to land on a target area, the target area consisting of a landing field with points for or against the player in accordance with the quality of the landing made, which quality is determined by the location on the landing field at which the projectile stops.

In the drawings:
Fig. 1 is a plan view of the landing field target;
Fig. 2 is a side elevation of the target;
Fig. 3 is a plan view of the projectile;
Fig. 4 is a side elevation of the projectile; and
Fig. 5 is a vertical section through a project-
ing means.

The first element of the game includes the target board 10 in the shape of an aircraft landing field and environment. This board has indicated on it crossing landing strips 11, the crossing preferably being indicated by a circle 12. Within the general area of the arms of the cross, but off the strips, there is an additional target area 13. Beyond the periphery of the area of the cross, there are edge areas 14 which may include trees and other indicated obstructions, these being here shown as trees 15 and buildings 16. Beyond the field entirely, there is a marginal band 18.

It will be seen that the center circle 12 of the landing strip carries the maximum point advantage, it being indicated at 50. The cross portions 11 of the landing strip carry plus scores of 25, as indicated. The area within the arms of the cross shown at 13 carries a plus score of 10. The portions adjacent the landing field having the trees 15 thereon carry minus scores of 10 points each, whereas the buildings 16 carry minus scores of 25 points each. The outer margin 18, outside the landing field entirely, carries a minus score of 50 points.

The projectile is generally indicated at 20 and is shown in Figs. 3 and 4. It is designed to act as a helicopter so that it will tend to sustain itself in the air upon being rotated, but will gradually descend under the action of gravity. It may be made simply or elaborately, as desired. A

simple illustration is here given as including a stem 21 at one end of which a propeller, generally designated at 22, is attached. This propeller may consist of a disc of cardboard or other suitable material with an opening cut out so that it may be slipped over and secured to the upper part of the stem 21. This strip is slotted at 24 a proper number of times, here shown as six, so as to get six blades, these blades being indicated at 25. There is an internal cut-out 26 to be disposed over the stem 21, and it will be observed that the slits 24 preferably do not extend inwardly to this cut-out 26.

15 The blades 25 are bent as shown in Fig. 4, so that, when the device is twirled counterclockwise in Fig. 3 and to the right in Fig. 4, the blades will tend to lift the whole device. The helicopter is of light weight, the stem being preferably of wood. Stabilizing weights 27 are desirably located beneath the edge of each of the blades. These act as inertia weights to keep the device spinning. The total weight is adjusted so that, when the helicopter is projected upwardly and spun, it will descend relatively slowly, with the longer 20 end of the stem downward.

23 end of the stem downward.
24 The stem 21 has one or more pins 29 projecting slightly therefrom.

While the helicopter may be spun manually if desired, it is preferable to have a projector for it such as that shown in Fig. 5. This projector has a base 31 made of wood or the like, to which a tube 32 is attached. This tube is desirably pivotally attached as shown at 33, so that it may be turned to a suitable direction for aiming purposes. Suitable friction by any convenient means may be had for retaining the tube in an adjusted position of angularity.

The tube has a rifling spiral 34 in its upper portion into which the pin 29 engages when the stem 21 is lowered into the tube 32. The tube likewise has a plunger 35, or the like, vertically reciprocable in it. This plunger has a pin 36 in it that is engageable within a slot 37 in an operating handle 38. This handle is preferably supported pivotally at 39 on the side of the tube. The outer end 40 of this lever 38 is the handle portion.

To play the game, the operator deposits a helicopter into the projector, so that the stem descends in the tube and the pin 29 engages in the rifling. In this operation, the handle 40 will be lifted. The device is then aimed, as desired, and a sharp descending force is applied to the handle 40. This discharges the helicopter from the tube and spins it in a direction tending to

lift it. It also directs it toward the target, which may be of any suitable size.

If the helicopter descends onto the target, the player is credited or charged with points in accordance with the place where the helicopter lands. Thus, if it lands at the center of the landing strip, the player is credited with 50 points. The other positive scores are obtained by other landings within the general area of the landing cross, or upon it. If, however, the helicopter strikes a tree or a building bordering the landing strip, the player is charged with a minus score in the amounts indicated. If he entirely misses the landing field, and lands on the marginal area, he is charged with the maximum minus score.

It will be seen that a game is provided which contains the element of skill in aiming and operating the helicopter. It also contains an element of chance because of the difficulty in obtaining accurate travel of the helicopter. As noted, it may be played by manual spinning of the helicopter, if such is desired.

What is claimed is:

1. A game projectile, comprising a short cylindrical body having a stud-like projection normal to the surface adjacent the lower end thereof, and a blade assembly fitted over the upper end of the body and secured thereto, said blade assembly including a disc with a series of radial slots formed therein extending from a point adjacent the center of the disc to the outer periphery thereof, the blade areas between the slots being canted to lift the projectile when the body is rotated in one direction, and individual weights secured to the blades adjacent the outer edges thereof.

2. A projecting device for use with a toy projectile, comprising a base, a tube-like member having a spiral groove formed in the inner wall thereof mounted on said base so that its angular position with respect to said base can be varied at will, a piston reciprocably mounted within the tube-like member, and manually operated means for actuating said piston so that the amount of force exerted by the piston can be varied at the will of the operator.

3. In combination, a projectile containing a stem having a stud-like projection extending transversely adjacent the lower end thereof; a disc-like member fastened adjacent the upper end of the stem and containing a series of radial slots extending to the outer periphery thereof, the areas between the slots being canted to form blades to lift the projectile when the stem is rotated in one direction; and a projecting device for launching the projectile including a tube-like member to receive the stem and containing a spiral groove in the inner wall thereof for engagement with the stud-like projection, a piston reciprocably mounted within the tube-like member below the stem for engagement with the end thereof, and a lever member for manually actuating said piston to eject the stem from the tube-like member with a force which can be varied at the will of the operator.
